UNITED STATES PATENT OFFICE.

JACOB A. BRADLEY, OF WABENO, WISCONSIN.

CLOTHES-PIN.

1,106,487.

Specification of Letters Patent. Patented Aug. 11, 1914.

Application filed July 21, 1913. Serial No. 780,115.

To all whom it may concern:

Be it known that I, JACOB A. BRADLEY, a citizen of the United States, and resident of Wabeno, in the county of Forest and State 5 of Wisconsin, have invented certain new and useful Improvements in Clothes-Pins; and I do hereby declare that the following is a full, clear, and exact description thereof.

My invention consists in what is herein 10 particularly set forth with reference to the accompanying drawings and pointed out in the claims of this specification, its object being to provide simple, economical and efficient spring-wire clothes-pins designed to 15 be strung on clothes-lines.

Figure 1 of the drawings represents a side elevation of a spring-wire clothespin in accordance with my invention and illustrates the application of the pin to a clothesline 20 and material hung thereon; Fig. 2, a sectional view on the plane indicated by line 2—2 in Fig. 1, and Fig. 3, a similar view on the plane indicated by line 3—3 in said Fig. 1.

Referring by numerals to the drawings my clothespin consists of a single non-corrosive 25 spring-wire bent and twisted to form an eye-shank 4, parallel circular loops 5 and fingers 6 crossing the loops in opposite directions. 30 Each finger embodies two stretches of the wire that is recurved in the fashioning of said finger to an approximately triangular shape as shown in Fig. 1, the ends of said wire being laid close against the opposing 35 stretch thereof. The fingers are preferably dished to normally bear against the opposing circular loops 5 of the wire beyond which they extend.

Caught in the eye of the shank 4 of the 40 clothespin is one eye-end 7 of a single suitably bent wire hanger, the other eye-end 8 of the hanger being for the engagement of a clothesline 9. The wire of the hanger is crossed to form the eye 7 and the remain-

der of said wire bent to form parallel loops 45 constituting the eye 8.

In practice the hangers of a series of clothespins similar to the one above specified are strung on a clothesline to be convenient to the person hanging clothes thereon, 50 and material 10 hung on the line is gripped between a loop 5 and finger 6 of a pin that is forced into working position, the point of said finger being flaring beyond said loop to 55 facilitate the operation.

A hanger in connection with the clothespin is convenient for the purpose specified but it may be omitted or not employed on a clothesline without departure from my invention as herein claimed for said pin. 60

I claim:

1. A clothespin consisting of a spring-wire bent and twisted to form a shank, parallel circular loops and fingers crossing the loops in opposite directions, each finger embodying two stretches of the wire that is recurved to fashion said finger in which an end of said wire is laid close against an opposing stretch of the same. 65

2. A clothespin consisting of a spring-wire bent and twisted to form a shank, parallel circular loops and fingers crossing the loops in opposite directions, said fingers being dished to normally bear against the opposing circular loops. 70

3. A clothespin consisting of a spring-wire bent and twisted to form an eye-shank, parallel circular loops and fingers crossing the loops in opposite directions, together with a hanger caught in said shank. 75

In testimony that I claim the foregoing I have hereunto set my hand at Wabeno in the county of Forest and State of Wisconsin in the presence of two witnesses.

JACOB A. BRADLEY.

Witnesses:

JOHN G. HARTER,
M. O. BOCKAM.
